CASE FOR A TIME SWITCH OR THE LIKE

Robert Podall, Chicago, Ill., assignor to American Machine & Foundry Company, a corporation of New Jersey

Filed Dec. 8, 1967, Ser. No. 9,711

Term of patent 14 years

Int. Cl. D13—03

U.S. Cl. D26—13

FIG. 1

FIG. 2

FIG. 3

FIG. 5

FIG. 4

FIGURES 1 and 2 are front and rear perspective views, respectively, of my new design for a case for a time switch or the like; and

FIGURES 3, 4 and 5 are front elevational, top plan and side elevational views, respectively, of my new case for a time switch design.

The broken lines are for illustrative purposes only.

I claim:

The ornamental design for a case for a time switch or the like, as shown and described.
